United States Patent Office

Des. 225,895
Patented Jan. 9, 1973

225,895

SHOE VENDING MACHINE

Kiyomitsu Ohno, Naka 2-9-9, Kunitachi-shi,
Tokyo, Japan

Filed June 25, 1971, Ser. No. 157,075

Term of patent 14 years

Int. Cl. D20—01

U.S. Cl. D52—3

FIG. 1

FIG. 2

FIG. 3

FIG. 4

FIG. 1 is a front perspective view of a receiving case for vending shoes, showing my new design;

FIG. 2 is a front perspective view of FIG. 1 in an open position;

FIG. 3 is a right side elevational view thereof;

FIG. 4 is a rear elevational view thereof.

I claim:

The ornamental design for a shoe vending machine, substantially as shown.
